(**) Term: **14 Years**

(57) **CLAIM**

(21) Appl. No.: **29/311,227**

We claim the ornamental design for a cart conversion attachment, as shown and described.

(22) Filed: **Jan. 26, 2009**

DESCRIPTION

(51) **LOC (9) Cl.** **12-02**

FIG. 1 is a perspective view of a cart conversion attachment embodying our new design.

(52) **U.S. Cl.** **D34/27**

FIG. 2 is a front view of a cart conversion attachment embodying our design.

(58) **Field of Classification Search** D34/12-27;
280/79.11, 79.2, 79.3, 47.35, 47.34, 47.19

FIG. 3 is a rear view of a cart conversion attachment embodying our design.

See application file for complete search history.

FIG. 4 is a side view of a cart conversion attachment embodying our design.

(56) **References Cited**

FIG. 5 is an alternative side view rotated 180° from that depicted in FIG. 4 embodying our design.
